LEG BRACE

Arthur Seelert, Minneapolis, Minn.

Application September 20, 1947, Serial No. 775,166

5 Claims. (Cl. 128—80)

1

This invention relates to new and useful improvements in leg braces, and more particularly to leg braces of the type extending substantially the full length of the wearer's leg.

In certain diseases, such as poliomyelitis cases, the legs of the patient frequently become temporarily weakened or paralyzed, and in the treatment of such cases, the weakened leg must be supported in a suitable brace which may extend from the bottom of the foot to the thigh, or the full length of the leg. Such braces are adapted to support and retain the leg in a stiffened position because of the knee usually being in such a weakened condition that it cannot support the weight of the body.

There are now on the market various types of leg braces designed for such purposes, but to the best of my knowledge, none of these have proven entirely satisfactory, the most common objection thereto residing in their bulkiness, whereby they may be awkward to apply and wear, and also whereby they may be extremely difficult to conceal when worn under light clothing.

In devices of this general type, it is of utmost importance that they be so constructed as to provide the necessary support for the leg and, at the same time, it must be so designed as to be capable of being readily applied or removed from the patient's leg. It should also fit the patient with maximum comfort, and should be as light in weight as possible in order not to unnecessarily fatigue the patient, when attempting to move about from place to place.

The improved brace herein disclosed is a result of long and tedious experimental work in an attempt to provide a leg brace in which all of the objectionable features now inherent in present day leg braces, have been substantially entirely eliminated, and an object of the invention therefore is to provide such a device which is in the form of a light, skeleton-like frame, including vertically spaced means for encircling the leg to secure the brace thereto, such brace being capable of adequately supporting the leg in its extended position and without undue discomfort to the patient.

A further object is to provide a leg brace comprising upper and lower sections formed of laterally spaced side bars of small cross section, provided with suitable straps for securing the brace to the upper and lower portions of the wearer's leg in such a manner that when the brace is secured in position thereon, it will provide the necessary support for the leg without adding

discomfort to the wearer, and because of its compactness and close fitting, it is not likely to be noticeable under clothing worn over the brace by the patient.

5 A further object is to provide such a device having a novel knee joint locking mechanism embodying an operating member located adjacent to the upper end of the brace and adapted to partially encircle the wearer's leg, whereby it 10 may be conveniently operated by the user without attracting the attention of nearby individuals.

A further object is to provide a leg brace of the character described in which the side bars of the upper and lower sections are longitudinally adjustable, whereby the brace may be adapted 15 to legs of different individuals with the assurance that the knee joint may always be accurately positioned with respect to the wearer's knee.

Other objects of the invention reside in the 20 specific construction of the locking means for the knee joint which includes a pair of forked latch elements pivoted to the lower ends of the side bars of the upper section, and each latch member having one end adapted to abuttingly

25 engage abutments provided on the upper ends of the side bars of the lower section, and spring-actuated operating rods being pivotally connected to said latch members and extending upwardly adjacent to the side bars of the upper section 30 and having their upper end pivoted to an arched shaped operating member having its ends pivotally connected to the side bars of the upper section, whereby said operating member partially encircles the wearer's leg and is conveniently 35 located at the front of the wearer's leg whereby the wearer may conveniently manipulate the operating member to release the latch elements, when the patient or person wearing the brace desires to bend his knee, as when assuming a

40 sitting position; in the construction of the stirrup provided at the lower end of the brace which is designed to accurately fit the bottom of the wearer's foot, and whereby said stirrup may be inserted into a conventional shoe without adding 45 discomfort to the wearer, the pivotal connections between said stirrup and the lower ends of the side bars of the lower section of the brace being accurately located with respect to the ankle joint, whereby the wearer's ankle is free to pivot in a normal manner; and in the provision of a leg brace of the character described which is highly 50 efficient and practical in operation, and which presents the utmost in comfort to the wearer.

Other objects of the invention will appear from 55 the following description and the accompanying

drawings and will be pointed out in the annexed claims.

In the accompanying drawings there has been disclosed a structure designed to carry out the various objects of the invention, but it is to be understood that the invention is not confined to the exact features shown, as various changes may be made within the scope of the claims which follow.

In the drawings:

Figure 1 is a side view showing the brace in its normal upright position;

Figure 2 is a front view of the brace;

Figure 3 is a view similar to Figure 1, but showing the upper portion of the brace disposed at an angle to its lower portion, as when the wearer assumes a sitting position;

Figure 4 is a detail sectional view on the line 4—4 of Figure 1, on an enlarged scale;

Figure 5 is a detail sectional view on the line 5—5 of Figure 1, on an enlarged scale, showing the means for locking the upper and lower brace sections in the position shown in Figure 1;

Figure 6 is an enlarged detail view, partially in section, showing one of the joints for pivotally connecting together the upper and lower sections of the brace;

Figure 7 is a similar view but showing the parts in the position assumed when the wearer's leg may be bent at the knee; and

Figure 8 is a detail sectional view on the line 8—8 of Figure 6.

The novel brace herein disclosed is shown comprising upper and lower sections, generally designated by the numerals 2 and 3, respectively, which are pivotally connected together by a knee joint generally designated by the numeral 4, which is accurately located with relation to the wearer's knee joint, whereby the wearer may freely bend his knee, when assuming a sitting position, without discomfort from the brace.

The upper section 2 is shown comprising spaced side bars, indicated by the numerals 5 and 6, each composed of two parts 7 and 8 which are adjustably secured together by suitable screws 9 received in spaced threaded apertures 11 provided in the intermediate portions of the lower parts 8, as indicated in Figure 3. The upper ends of the lower parts 8 are shown provided with integrally formed loops 10 adapted to receive the upper bar parts 7 to retain the upper and lower parts of each side bar in operative relation, when the screws 9 are released for the purpose of varying the overall length of the upper section.

The upper ends of the upper side bar parts 7 of section 2 are shown secured together by a semi-cylindrical member 12, indicated in dotted lines in Figures 1 and 3. This member partially encircles the leg and for practical reasons may be integrally formed with the depending bar parts 7, as will be understood. The member 12 is enclosed within a strap-like covering member 13 adapted to completely encircle the leg. A suitable strap and buckle fastening device 14 is utilized to secure the upper end of the brace to the wearer's leg. The covering member 13 may be made of any suitable material such as leather, and a suitable padding, not shown, may be provided around the annular member 12 within the member 13, whereby the upper portion of the brace may fit the wearer's leg without chafing or otherwise adding to the discomfort of the wearer.

The lowermost ends of the parts 8 of the side bars 5 and 6 are preferably formed with enlarged disk-like heads 15, shown fitted between spaced

disk elements 16—16, provided at the upper end of the side bars 17 and 18 of the lower section 3. In other words, the upper ends of the side bars 17 and 18 of the lower section 3 of the brace are "forked" to receive the disk-like heads 15 of the side bars 5 and 6 of the upper section, as clearly illustrated in Figures 6, 7 and 8. Pivot pins or screws 19 pivotally connect the parts together, as shown in the drawings and cooperate with the disk-like elements 15 and 16 to provide very substantial and rugged knee joints between the side bars of the upper and lower sections of the brace, as will be understood.

To limit relative pivotal movement between the upper and lower sections 2 and 3, the disk-like element 15 of each side bar 5 and 6 of the upper section are shown provided with faces 21 and 22, adapted to alternately engage the bottom 23 of the fork or slot provided between the disk-like elements 16 at the upper ends of the side bars of the lower section. By so constructing the parts of each joint, the upper section will be limited in its forward swinging movement to the position shown in Figure 1, whereby the wearer's leg will be in its normal straightened position. The abutment face 22 is so located with respect to the abutment face 21 that the brace may adapt itself to any normal bending of the wearer's knee without discomfort to the wearer.

The lower section 3 is longitudinally adjustable in a manner similar to the upper section 2, whereby the knee joint provided by the pivot pins 19 may be accurately positioned with respect to the wearer's knee. To thus longitudinally adjust the lower section, the side bars 17 and 18 of said section are shown each comprising upper and lower parts 24 and 25, respectively, the upper parts 24 being relatively longer than the lower parts 25. Guide loops 26 are provided at the lower ends of the bar parts 18 through which the lower parts 25 are slidable, as shown. The upper parts 24 are provided with spaced apertures 27 threaded to receive clamping screws 28 which secure the parts 24 and 25 in fixed adjusted positions. The screws 28 and apertures 27 thus provide means whereby the lower section 3 may be longitudinally adjusted in a manner similar to the upper section 2.

A connecting member 29 is shown integrally formed with the parts 24 of the side bars of the lower section 3, and is adapted to be fitted against the rear portion of the wearer's leg, as best shown in Figures 1 and 3, said member being suitably padded with a material such as leather, or the like, to prevent the metal from directly contacting the operator's leg.

A strap 31 has one end secured to one of the side bars of the lower section, as shown at 32, and the opposite end of said strap is adapted to engage a buckle 33 secured to the other side bar of the lower section. A suitable pad 34 may be secured to the strap 31 to cushion the engagement of the strap 31 with the wearer's leg, when the brace is strapped onto the leg.

A stirrup, generally designated by the numeral 35, is shown pivoted to the lower ends of the side bars 17 and 18 of the lower section 3 of the brace by suitable pivot bolts or screws 36. A suitable leather pad or cushioning element 37 is preferably secured to the upper face of the stirrup 35 to prevent direct contact of the wearer's foot with the metal constituting the stirrup.

One of the outstanding features of the present invention resides in the means provided for locking the upper and lower sections of the brace in

their normal upright positions, as shown in Figures 1 and 2. In a brace such as herein disclosed, it is of utmost importance that the knee joint of the brace be so constructed that there is no play in the parts when the brace is worn, because any play allowed in the knee joint of the brace may result in the development of an unpleasant clicking noise, when the wearer is moving about.

To thus lock the upper and lower sections in their normal positions, as shown in Figure 1, latch members 38 are shown pivoted to the lower portions of the side bars 5 and 6 of the upper section by suitable pivot pins or screws 39. The latch members are preferably forked, as shown in Figure 5, whereby the spaced legs 41 thereof straddle the lower ends of their respective side bars 5 and 6, whereby each latch member 38 is provided with a relatively wide abutting face 42 adapted to abuttingly engage abutments 43 provided on the disk-like members 16 of the upper ends of the side bars 17 and 18 of the lower section 3. The abutments 43 are so related to the terminal faces 42 of the latch members 38 that when the upper brace section 2 is positioned, as shown in Figure 1, the latch members 38 will snugly engage the abutment faces 43 to thereby positively prevent any play in the joints when the brace is in its normal extended position.

To release the latch members 38 from the abutments 43 to permit the wearer to bend his knee, a suitable latch-operating member, generally designated by the numeral 44, is shown pivotally mounted on the upper parts 7—7 of the side bars 5 and 6 of the upper section, as clearly illustrated in Figures 1 to 4, inclusive. The arcuately formed portion 45 of the operating member is shown having one end portion provided with a reduced threaded terminal 46, received in a threaded socket provided in an end piece 47 which is pivoted to the part 7 of the side bar 6. A similar end piece 47 is similarly pivoted to the upper portion of the side bar 5 of the upper section, and has a terminal socket adapted to receive a reduced terminal 48 provided at the opposite end of the arcuately formed latch-operating member 45.

Suitable connecting rods 49 have their lower ends connected to the latch members 38, and their upper ends are shown connected to the end pieces 47 of the latch-operating member 44, as clearly illustrated in the drawings, whereby when the latch-operating member 45 is shoved downwardly with respect to the wearer's leg, the latch members are moved out of locking engagement with the abutments 43, thereby permitting relative swinging movement of the upper brace section 2, with respect to the lower brace section 3, as shown in Figure 3.

Suitable springs 51 are shown operatively connected to the connecting rods 49 and constantly urge said rods in an upward direction, as shown in Figure 1, to thereby cause the latch member to automatically snap into locking engagement with the abutments 43, when the upper section 2 is moved into its normal extended or upright position, shown in Figure 1.

In the operation of fitting the brace onto an individual's leg, the portion 45 of the latch-operating member 44 has its reduced terminal 48 disconnected from the end piece 47 pivoted to the side bar 5 of the upper section, and the operating member may then be outwardly swung to the dotted line position shown in Figure 4, whereby the upper section may readily be fitted onto the wearer's thigh. The manipulation of

suitable straps and buckles shown at 52 and 53, secured to the upper brace section 2 are arranged to encircle the wearer's leg in the usual manner, as will be understood by reference to the drawings.

Another feature of the present invention resides in the novel design and construction of the various parts of the brace. By referring to the drawings, it will be noted the side bars of the upper and lower sections are extremely small in cross section, and are so designed and shaped as to fit closely to the sides of the wearer's leg, thereby to eliminate bulkiness, as much as possible, whereby the brace may be worn by an individual under conventional garments and without discomfort and without being conspicuous, as is frequently the case with well known braces now in common use.

It must also be observed that a very small portion of the wearer's leg is completely enclosed within the brace. By thus reducing the leg encircling portions of the brace, greater comfort is obtained in that air may circulate freely around the leg in a normal manner and, in addition, it makes it possible to greatly reduce the weight of the brace, as a whole.

The stirrup 35 pivotally connected to the lower ends of the side bars of the lower section 3 has been carefully designed to permit it to be worn within a conventional shoe without adding discomfort to the wearer. The stirrup is amply large to adequately support the instep of the wearer's foot, and cooperates with the side bars 17 and 18 of the lower section to adequately support the ankle. Also because of the unique design of the side bars of the lower section 3, stockings worn by the wearer may completely and thoroughly conceal the brace which is a highly desirable feature in devices of this general character.

The location of the latch-operating member 44 is also important in that it is so located that the wearer may readily manipulate the device to permit bending of the knee at any time without attracting the attention of nearby individuals. By locating the latch-operating member adjacent to the upper end of the brace, and extending it across the front of the wearer's leg or thigh, the operating member 44 is within convenient reach at all times, which is not true with many conventional braces now in common use, and some of which require the pulling of cords or other such elements to release the locking means between the upper and lower sections of the brace.

It will be apparent to those skilled in the art that I have accomplished at least the principal objects of my invention, and it will also be apparent to those skilled in the art that the embodiments herein described may be variously changed and modified without departing from the spirit of the invention, and that the invention is capable of uses and has advantages not herein specifically described; hence it will be appreciated that the herein disclosed embodiments are illustrative only, and that my invention is not limited thereto.

I claim as my invention:

1. In a leg supporting brace having a pair of spaced lower brace sections connected by pivotal knee joints to a pair of spaced upper brace sections, an abutment member on each member of one of said pairs of sections and a movable stop on each member of the other of said pairs of sections, said movable stops adapted to en-

gage said abutment members for locking said knee joints against pivotal movement, the improvement comprising handle means comprising an arcuate portion and spaced terminal portions, each of said terminal portions being pivoted at one end to one member of said upper brace sections, one terminal having the other end rotatably receiving one end of said arcuate portion, and the other terminal detachably receiving the other end of said arcuate portion and means connecting said terminal sections to said movable stops for the operation thereof whereby the operation of said handle means will determine the engagement or disengagement of said movable stops with said abutments.

2. The apparatus of claim 1 further characterized in that said other terminal contains a socket and said other end of the arcuate portion consists of a plug for said socket.

3. The apparatus of claim 1 further characterized in that said arcuate portion has one end threadably pivoted on one of said terminal portions, whereby it may be swung from an operative position surrounding a segment of a leg to an inoperative position adjacent thereto in which the leg may be readily removed from said brace.

4. The apparatus of claim 3 further characterized the other end of said arcuate portion being engageable in a socket in the other of said terminal portions whereby said non-threaded end of said arcuate portion may be removed from said socket and said arcuate handle portion pivoted about said threaded engagement with the said other terminal portion whereby a leg may be inserted in the leg brace with substantial ease.

5. In a leg supporting brace having a pair of spaced lower brace sections, connected by pivotal knee joints to a pair of spaced upper brace

sections, an abutment member on each member of one of said pairs of sections and a movable stop on each member of the other of said pairs of sections, said movable stops adapted to engage said abutment members for locking said knee joints against pivotal movement, the improvement comprising handle means comprising an arcuate portion and spaced terminal portions, each of said terminal portions being pivoted at one end thereof to one member of one of said pairs of brace sections, the other ends of said terminals connected to the ends of said arcuate portion, at least one of said terminals having said other end thereof frictionally detachably connected to the end of said arcuate portion, and means connecting said terminal sections to said movable stops for the operation thereof whereby the operation of said handle means will determine the engagement or disengagement of said movable stops with said abutments.
